UNITED STATES PATENT OFFICE.

GEORGE SPALDING, OF STOCKTON, CALIFORNIA, ASSIGNOR TO SPALDING PLOW COMPANY, OF PITTSBURG, PENNSYLVANIA, A CORPORATION OF PENNSYLVANIA

WHEEL-BEARING.

988,219.

Specification of Letters Patent. Patented Mar. 28, 1911.

Application filed December 30, 1908. Serial No. 470,037.

To all whom it may concern:

Be it known that I, GEORGE SPALDING, of Stockton, in the county of San Joaquin, State of California, have invented certain new and useful Improvements in Wheel-Bearings, of which the following is a specification.

This invention contemplates certain new and useful improvements in wheel bearings, 10 and relates more particularly to that class of bearings employed in connection with the wheels of tilling machines, and other agricultural implements.

The invention has for its object to provide 15 a wheel bearing of simple construction, possessing sufficient strength to sustain the weight of the machine and to withstand the strains incident to the operation thereof.

A further object is to provide means for 20 protecting the oil cups or other lubricating devices used in connection with the machine from injury during the operation of the latter.

A further object is to provide simple and 25 efficient means for preventing rotation of the bearing sleeve.

The invention will be hereinafter fully set forth and particularly pointed out in the claims.

30 In the accompanying drawings:—Figure 1 is an inner end view of my improved bearing illustrating the same mounted upon an axle. Fig. 2 is a longitudinal sectional view. Fig. 3 is an outer end view, with the 35 bearing removed from the axle. Fig. 4 is an end view of a slight modification. Fig. 5 is a side view thereof.

Referring to the drawing, 10 designates 40 an arm constructed to depend from any suitable frame (not shown) and bent outwardly at its lower end to form an axle 12. I do not desire to limit myself, however, to this particular form. Mounted on the axle 12 is a bearing sleeve 13 provided at its inner 45 end with a flange 14, said flange being chambered at 15 to receive the end of the hub 16 of a wheel. The flange 14 is provided with a shoulder 18 which forms an abutment constructed to engage the arm 10, said abutment 50 being provided with a channel 19 leading from the oil cup 20, or other lubricating device, to the annular chamber 15. The channel 19 is preferably formed by casting within the shoulder 18, a pipe of the desired bore,

threaded at one end, thereby providing a 55 suitable thread at 21 for the attachment of the oil cup 20, but I do not desire to limit myself to this specific method of forming said channel 19. The oil cup is protected from injury by a pocket formed by the 60 abutment 18, a flange or web 22 formed integral with and extending from said abutment to the flange 14, and a wall 23 formed integral with and extending from the web 22 to the abutment 18, said wall being practically a continuation of the flange 14. The flange 14 and its extension 23, the abutment 18 and the web 22 are so arranged as to 65 cover or inclose the oil cup on three sides.

In Fig. 4 I have shown a slight modification of my improved wheel bearing, the same being designed for steering wheels such as illustrated and described in a pending application filed by me. In said figure I have illustrated the web 22 as provided with a 70 table or enlargement 24 to support the weight of the frame, said table or enlargement being concaved at 25 to fit closely around the steering shaft 26.

In practice the wheel is secured in position by means of the usual nut and washer, the abutment 18 serving to prevent rotation of the sleeve 13 upon the arm 11. The oil cup being located within a pocket provided with three protecting walls, is not liable to 85 be injured during the operation of the machine. In this connection it will be noted that the lubricant is fed in through the oil cup and works outwardly through the bearings, and by its flow prevent sand or other 90 impurities from getting to the wearing parts.

I claim as my invention:—

1. A wheel bearing comprising a tapered sleeve provided with an annular flange at its larger end and a longitudinal bore to receive the axle, the outer face of said flange being provided with an integral solid projection extending to the periphery of the flange and forming an abutment to engage a portion of said axle to prevent rotation of 100 said sleeve, the inner face of said flange being provided with an annular groove to receive one end of a wheel hub.

2. A wheel bearing comprising a sleeve constructed to receive an axle and having a 105 flange at one end, said flange being provided with an integral enlargement forming an abutment arranged to engage said axle to

- prevent rotation of said sleeve, said abutment being provided with a channel for lubricant.
3. A wheel bearing comprising a sleeve having a flange at one end provided with a shoulder forming an abutment to prevent rotation of said sleeve, and a pipe inclosed within said abutment and forming a channel for lubricant.
- 10 4. A wheel bearing comprising a sleeve constructed to receive an axle and having a flange at one end provided with an annular chamber to receive the hub of a wheel, said flange being provided with an integral enlargement forming an abutment arranged to prevent rotation of said sleeve, said abutment being provided with a channel for lubricant leading to said annular chamber.
- 15 5. A wheel bearing comprising a sleeve having a flange at one end provided with a shoulder forming an abutment to prevent rotation of said sleeve, said shoulder being constructed to support a lubricating device, and an integral protecting web extending 20 out from said flange and joining one edge of said shoulder.
- 25 6. A wheel bearing comprising a sleeve having a flange at one end provided with a shoulder forming an abutment to prevent rotation of said sleeve, said shoulder being constructed to support a lubricating device and an integral protecting web extending 30 out from said flange and joining one edge of
- said shoulder, and a wall extending from said web to said abutment, said flange, web 35 and wall coöoperating to form a pocket.
7. A wheel bearing comprising a sleeve having a flange at one end provided with a shoulder forming an abutment to prevent rotation of said sleeve, said flange being provided with an integral web joining one edge 40 of said shoulder, said web being flattened on its top to form a frame supporting table or rest.
8. A wheel bearing comprising a sleeve 45 having a flange at one end provided with a shoulder forming an abutment to prevent rotation of said sleeve, said flange being also provided with a flattened portion forming a frame supporting table or rest.
9. A wheel bearing comprising a sleeve having a flange at one end provided with a shoulder forming an abutment to prevent rotation of said sleeve, said flange being also provided with a flattened portion forming a frame supporting table or rest, said table being provided with a concaved portion 50 constructed to receive a shaft.

In testimony whereof, I have signed this specification in the presence of two subscribing witnesses.

GEORGE SPALDING.
